UNITED STATES PATENT OFFICE.

EDWARD L. ANDERSON, OF ATTLEBORO, MASSACHUSETTS, ASSIGNOR TO R. AND G. COMPANY, OF ATTLEBORO, MASSACHUSETTS.

COLLAR-BUTTON.

1,107,190.

Specification of Letters Patent.

Patented Aug. 11, 1914.

Application filed February 24, 1914. Serial No. 820,738.

To all whom it may concern:

Be it known that I, EDWARD L. ANDERSON, a citizen of the United States, residing at Attleboro, in the county of Bristol and State 5 of Massachusetts, have invented a new and useful Improvement in Collar-Buttons, of which the following is a specification.

This invention relates to certain new and useful improvements in collar buttons, and 10 the primary object thereof is to provide improved means for effecting connection of the post with the pearl back.

A further object of the invention is to provide means for uniting the post and back 15 which will effectively retain the parts in rigid connected relation, and which will prevent contact of the more or less raw edges of the post base with the body or clothes of the wearer.

20 In the drawings—Figure 1 is a side elevation partly broken away and in section showing the parts related prior to completion. Fig. 2 is a similar view of the completed collar button, and Fig. 3 is a view similar to Fig. 2 of a modified form of the invention.

In proceeding in accordance with the present invention the pearl back 1 has a central aperture 2 and a countersunk portion or depression 3 which is concentric to the aperture 2.

30 The post 4 which is of tubular form has its base portion doubled upon itself at 5 to provide a bearing or abutment which seats on the inner face of the back 1. The end 6 of the post base which is extended out from 35 the bearing or abutment 5 projects through the aperture 2 as shown in Fig. 1 after which its free end portion is spun or swaged into the countersunk part or depression 3, as illustrated in Fig. 2, in which position it 40 will be seen that the raw edge of the end 6 is disposed inwardly of the outer face of the back 1, and is thereby protected by the same, preventing contact of the raw edge with the clothing of the wearer. The protection of 45 the raw edge of the end or extension 6 is complete and effective and overcomes an objection which has heretofore proven difficult of solution. Preferably, when swaged or spun into the position illustrated in Fig. 2

50 of the drawings, the raw edge of the end or extension 6 contacts with the wall which defines the countersunk part or depression 3, thus contributing to the effective and rigid

anchorage of the back 1 to the post. By 55 doubling the post over to provide the bearing or abutment 5, the base of the post is materially strengthened, and in addition, a solid and rigid part is provided which acts as an anvil so to speak during the swaging 60 of the end or extension 6.

In the modified form of the invention depicted in Fig. 3 of the drawings, the sole distinction presented is that of the tapered bottom wall 3' of the depression or countersunk part 3, and the corresponding change in 65 the conformation of the end of the post which is swaged or spun so as to conformably engage the tapered bottom wall 3', the extension or end of the post thus having a 70 tapered or flared portion 7.

In both forms of the invention, the swaged or spun end of the post co-operates with the thickened or enlarged doubled portion 5 to firmly clamp the pearl back in position, and since the doubling over of the post to form 75 the bearing 5 provides a rounded edge for same, and due to the fact that the raw edge of the extension is disposed between the inner and outer faces of the pearl back, it will be apparent that no rough edges or other 80 parts of the base metal are exposed which would prove objectionable for manifest reasons.

Having thus described my invention, I claim as new and desire to secure by Letters 85 Patent:—

1. In a collar button, a tubular post having a doubled over part disposed in spaced relation to the end of its base portion to provide an abutment, the post being extended 90 beyond the doubled over part, and a pearl back having a central aperture through which said post extension is projected, and also having a countersunk portion into which the end of the extension is outwardly swaged 95 so as to cause the swaged portion to be disposed between the inner and outer faces of the back and to have its periphery covered by the bounding wall which said countersunk portion provides.

2. In a collar button, a tubular post having an abutment and an extension which projects beyond the abutment, and a back which has a central aperture through which said extension projects and also having a 105 countersunk part into which the free end

portion of the extension is outwardly swaged so that the outer face of the back extends beyond said swaged portion and the latter has its periphery covered by the bounding wall which said countersunk portion provides.

In testimony whereof I have signed my

name to this specification in the presence of two subscribing witnesses.

EDWARD L. ANDERSON.
